UNITED STATES PATENT OFFICE.

JOACHIM T. HOLTFOOTH, OF KALAMAZOO, MICHIGAN.

SHUTTER-OPERATING DEVICE.

1,104,118.

Specification of Letters Patent. Patented July 21, 1914.

Application filed October 1, 1912. Serial No. 723,328.

To all whom it may concern:

Be it known that I, JOACHIM T. HOLTFOOTH, a citizen of the United States, residing at the city of Kalamazoo, Michigan, ⁵ have invented certain new and useful Improvements in Shutter-Operating Devices, of which the following is a specification.

This invention relates to improvements in shutter operating devices.

10 The main objects of my invention are,— First, to provide an improved automatic shutter operating device. Second, to provide an improved shutter actuating mechanism by means of which the shutter is automatically opened and closed. Third, to provide an improved automatic shutter actuating mechanism by means of which the opening and closing of the shutter is effectively timed. Fourth, to provide a device ¹⁵ having these advantages, which is simple in structure and operation.

Further objects, and objects relating to structural details, will definitely appear from the detailed description to follow.

25 I accomplish the objects of my invention by the devices and means described in the following specification.

The invention is clearly defined and pointed out in the claims.

30 A structure which is a preferred embodiment of my invention is clearly illustrated in the accompanying drawing, forming a part of this specification, in which:

Figure I is a side elevation of a structure ³⁵ embodying the features of my invention, a camera shutter being illustrated in connection therewith. Fig. II is a detail vertical section on a line corresponding to line 2—2 of Fig. III. Fig. III is a horizontal section ⁴⁰ on a line corresponding to line 3—3 of Fig. II. Fig. IV is a detail section through one of the valves on a line corresponding to line 4—4 of Fig. III, the valve plug being shown in full lines. Fig. V is a detail section ⁴⁵ on a line corresponding to line 5—5 of Fig. IV.

In the drawing similar reference characters refer to similar parts throughout the several views, and the sectional views are ⁵⁰ taken looking in the direction of the little arrows at the ends of the section lines.

Referring to the drawing, the barrel or cylinder 1 is connected by the tube 24 to the pneumatic shutter engine 25. This shutter engine 25 is of the well-known plunger

type such as is commonly actuated by means of a hand bulb. As the structure of these engines is well understood, I do not describe the same in detail herein.

The nipple 23 connecting the tube 24 to the cylinder 1 is disposed at one end of the cylinder 1. The cylinder is provided with an inlet valve at its outer end and an exhaust valve at its inner end,—that is, the end to which the tube 24 is connected.

Reciprocating within the cylinder between these valves, is a piston ¹⁵ having a rod 2 arranged through the packing gland 11 in the head 10 of the cylinder. The rod 2 is provided with a finger piece 3. The piston ⁷⁰ is actuated by means of the coiled spring 9. The piston is shown in its outer position. To retain the piston in this position, I provide a catch 12 which is pivoted at 13 to engage a keeper 4 on the piston rod. ⁷⁵

Between the valves 7, the cylinder is provided with a port or opening 6 across which the piston reciprocates. The casings of the valves 7 are provided with passages or ports ¹⁵ opening into the cylinder and with ports ⁸⁰ 16 opening to the atmosphere.

The rotary valve plugs ¹⁸ are provided with peripheral tapered passages 19. See Fig. V. The object of thus forming the valve passages is to enable the accurate adjustment of the valves and thus secure the timing. The valves are provided with disk-like finger pieces 17 having index numerals thereon. Index fingers 17' are provided to coact with the index disks. ⁹⁰

In the operation of my improved actuating device, the piston is pushed to its outer position as shown in the drawing, by means of the finger piece 3 on the stem 2. This compresses the actuating spring 9, thus storing power for actuating the piston. The valve at the outer end of the cylinder is set for the number of seconds it is desired shall elapse before the shutter is opened and the valve at the inner end of the cylinder is set ⁹⁵ for the number of seconds it is desired that the shutter shall remain open. When the catch 12 is released, the piston is actuated by the spring, its movement until it passes the port 6 being timed by the admission of air ¹⁰⁵ to the cylinder below the piston through the valve at the outer end of the cylinder. When the piston passes the port 6, the air is compressed in the inner end of the cylinder by the action of the piston and the ¹¹⁰

- shutter engine actuated to open the shutter and is held in its actuating position until the piston reaches the inner end of its stroke. During this period of the movement of the piston it is controlled by the exhaust valve at the inner end of the cylinder, thus timing the exposure. By this means, the device may be set so that the operator may position himself to be included in the picture.
- 10 In the structure illustrated, the index for the valves is designed for the valve in the closing position as shown in Fig. V. It is evident that it might be designed for the valve in closing position when the passage 15 19 is brought out of register with the passage 15.

I have illustrated and described my improvements in a simple embodiment. I have not attempted to illustrate or describe various modifications in structural details which I contemplate as such modifications will be readily understood by those skilled in the art to which this invention relates from the disclosure here made. I desire, however, 25 to be understood as claiming my improvements specifically in the form illustrated as well as broadly within the scope of the appended claims.

Having thus described my invention, what 30 I claim is new and desire to secure by Letters Patent is:

1. In a shutter operating device, the combination of a cylinder having a pneumatic shutter engine connection at one end; independently adjustable rotary valves provided with peripheral tapered passages disposed at the ends of said cylinder, said cylinder being provided with a port between said valves; indexes for said valves; a piston 35 reciprocating between said valves and across said port; and a spring arranged to actuate

said piston toward the said engine connection of said cylinder.

2. In a shutter operating device, the combination of a cylinder having a pneumatic shutter engine connection at one end; independently adjustable valves at the ends of said cylinder, said cylinder being provided with an opening between said valves; a piston reciprocating between said valves and across said opening; and a spring arranged to actuate said piston toward the said engine connection of said cylinder.

3. The combination of a cylinder provided with an actuated member connection; valves for said cylinder, said cylinder being provided with a port between said valves; a piston reciprocating between said valves and across said port; and a spring for actuating said piston toward the actuated member connection of said cylinder.

4. The combination of a cylinder provided with an actuated member connection, there being an inlet at the outer end of the cylinder and an exhaust at its inner end and an opening between said inlet and exhaust; a piston reciprocating between said inlet and exhaust and across said opening; and a spring for actuating said piston toward the exhaust thereof, whereby the movement of the piston on one side of said opening is controlled by the admission of air to the cylinder and its movement on the other side of said opening is controlled by the escape of the air.

In witness whereof, I have heretunto set my hand and seal in the presence of two witnesses.

JOACHIM T. HOLTFOTH, [L. s.]
